DESIGN.

H. SMITH.

HEATING STOVE.

No. 17,577.

Patented Aug. 2, 1887.

UNITED STATES PATENT OFFICE.

HOLMES SMITH, OF ST. LOUIS, MISSOURI.

DESIGN FOR A HEATING-STOVE.

SPECIFICATION forming part of Design No. 17,577, dated August 2, 1867.

Application filed June 21, 1867. Serial No. 242,046. Term of patent 14 years.

To all whom it may concern:

Be it known that I, HOLMES SMITH, a subject of the Queen of Great Britain, residing in the city of St. Louis, Missouri, have invented and produced a new and original Design for Heating-Stoves, of which the following is a specification, reference being had to the accompanying photograph, forming part thereof, in which the newly-designed stove is shown in perspective.

Upon the legs A rests a square base-plate, B, which in turn supports a square ash-pit, C, having a foot-rest, D, in front. The fire-pot E and combustion-chamber F, taken together, are globular, but truncated at the top, where the drum G rests upon the combustion-chamber; and at the bottom, where the fire-pot touches the ash-pit, a reverse curve, f, is introduced and the base of the fire-pot thereby enlarged. The drum G is cylindrical, and it

has a dome-shaped top, upon which rests an urn, H, having a tulip-shaped finial, h. The fire-pot appears in the form of open-work. Ornamentation appears upon the legs at a, upon the ash-pit at e, upon the combustion-chamber at f and f', upon the drum at g, and upon the drum-top at g', substantially as shown.

I claim—

The design for a heating-stove herein shown and described, the same consisting of the square base-plate, square ash-pit, the fire-pot, and combustion-chamber, shaped and ornamented as shown and described, the cylindrical drum with the dome-shaped top, and the urn.

Witness my hand.

HOLMES SMITH.
